UNITED STATES PATENT OFFICE.

RICHARD P. ELLIOTT, OF BOSTON, MASSACHUSETTS.

METHOD OF MAKING AND INCORPORATING STIFFENING-PIECES IN THE FOREPART OF BOOTS AND SHOES.

1,137,850.

Specification of Letters Patent. Patented May 4, 1915.

Application filed December 12, 1914. Serial No. 876,762.

To all whom it may concern:

Be it known that I, RICHARD P. ELLIOTT, a citizen of the United States, residing in Boston, county of Suffolk, State of Massachusetts, have invented certain new and useful Improvements in the Method of Making and Incorporating Stiffening-Pieces in the Forepart of Boots and Shoes.

My invention relates to the manufacture 10 of boots and shoes of the type wherein the toe parts having box toes are formed during the process of lasting, which box toes have a stiffening piece incorporated therein capable of being molded into the desired shape 15 during the lasting operation.

The object of the invention is to produce a stiffening piece for a box toe which will be durable, not affected by moisture, and not affected or softened by a degree of heat 20 which might be injurious to the material of the upper of the boot or shoe; and further, to provide for heating the stiffening piece to soften it after it is dry and incorporated in the upper of a boot or shoe by applying 25 the heat in such manner as not to injure said upper.

In carrying out the invention I provide a blank of absorbent, fibrous or textile fabric, capable of absorbing a stiffening fluid or 30 composition. A suitable composition or fluid may be made of a solution of shellac and alcohol, to which may be added a sufficient quantity of borax solution and alum dissolved in water. When desired, the 35 alum may be left out and but a small quantity of borax added to the shellac in order that the composition may be practically waterproof and so that it will require a degree of heat in excess of the boiling 40 point to soften the stiffening piece so it can be molded into the desired shape.

In the drawings accompanying this specification and forming a part thereof, Figure 1 represents a side elevation of a boot or 45 shoe upper placed on a last and with the stiffening piece inserted in a heating device to soften it preparatory to lasting the upper and molding the stiffening piece to the shape of the toe of the last; Fig. 2 represents a plan of a heater with sections of boot or shoe uppers with the stiffening piece in 50 place to be heated and softened; Fig. 3 is a vertical cross section taken through line 3—3, Fig. 2; Fig. 4 represents a plan of a 55 stiffening piece; and Fig. 5 is a cross section

of said stiffening piece taken on line 5—5, Fig. 4.

In the manufacture of boots and shoes having what is termed box toes, it is desirable to incorporate in the toe-part of the 60 upper a stiffening piece and mold it to the desired shape of the toe. It has also been found more desirable to incorporate the stiffening pieces in a boot or shoe upper while it is flat, and shape or mold the stiffening piece during the act of pulling over and 65 lasting the boot or shoe upper. To this end, I provide a stiffening piece 1 of approximately the shape shown in Fig. 4, preferably provided with the skived edge 2. The 70 skiving may, if desired, extend all around the edge of the stiffening piece 1.

When getting out parts composing a boot or shoe upper, they are usually composed of the upper 3, the heel-part of the vamp 4, 75 the forepart 5, and the toe-part 6. The forepart is usually skived to thin it down at the point where it is stitched to the toe-part 6 and to the stiffening piece 1 when it is desired to attach the stiffening piece to 80 the upper. Practically all boots and shoes are provided with a lining, as shown at 7, Fig. 3. When the shoe is finished the stiffening piece 1 lies between the toe-piece 6 and the lining 7.

In the process of lasting a boot or shoe, the upper is placed on a last in the right position and usually tacked at the back of the heel-part at the point 8, or thereabout. By fastening the upper of the shoe to the last in 90 this manner it permits the upper, which is flexible, to swing upwardly as shown in Fig. 1. By my method of making and incorporating the stiffening pieces in a boot or shoe upper, the stiffening piece is saturated 95 with the composition and allowed to dry. Thereafter, the stiffening piece is softened at so high a degree of heat as would be injurious to the material of a shoe upper. For that reason, the toe-piece of the upper and 100 the lining are turned back, as shown in Figs. 1 and 2, so that the stiffening piece may be inserted in the heater 9 and softened up without heating the lining and the toe-piece. The heater 9 is provided with the insulating 105 guards 10, 10, which protect the lining and toe-piece from the heat generated in the heater 9.

For the purpose of illustration, I have shown a form of electric heater, but any 110

other method of heating may be used, such as gas, steam, or other means which will generate sufficient heat to soften the stiffening piece 1.

- 5 In carrying out my method of making and incorporating a stiffening piece in a boot or shoe, I provide the heater 9 with the insulating pieces 10, 10, the heater being provided with suitable supports, as 11, 11, to 10 raise it, so that for convenience the last 12 may project slightly under the heater. The last may be supported upon a rack 13 so as to bring the toe-part of the boot or shoe upper to a position where the stiffening piece 15 1 may be easily inserted in the heater. In the heater shown, 14 is the body part of the heater, which may be an inclosed metal body and which may contain the heating coils 15, 15, etc. I also provide wire protectors 16, 20 16, etc., to guide the stiffening piece 1 and to prevent it from coming in contact with the heating surface of the heating coils 15, 15, etc., when an electric heater is used. The guards 10, 10, may be made of any suitable 25 non-conducting material, such as asbestos and the like.

As before stated, I do not confine the stiffening fluid or composition with which the toe-piece is saturated to shellac, or shellac and borax, or shellac, borax and alum composition, as any other suitable waterproof, and low-heat-proof composition may be used for stiffening the fibrous material, or textile fabric; nor do I confine my invention to an electrical heater, or the exact form of an electrical heater shown in the drawing, when such type of heater is used, as any form of electrical heater may be used which will generate a sufficient amount of heat to 30 soften the stiffening piece; and further, other forms of heating devices, such as steam, or a gas heater, may be used. My invention resides particularly in providing a composition that will be practically water- 35 proof and that will not soften up under the ordinary degree of heat; such for instance, if the wearer of a boot or shoe should hold his foot close to or against a steam radiator,

the heat generated in such case would not be sufficient to soften the toe-piece. Further, 50 I provide means for softening the toe-piece so it can be molded without liability to injure or overheat the lining or toe-piece of a shoe.

What I claim is—

1. The method of making stiffened fore-parts of boot and shoe uppers, which consists in incorporating in the boot or shoe upper before lasting, a dry stiffening piece composed of a fibrous material containing a 60 stiffening composition or material adapted to be softened by a degree of heat which might be injurious to the boot or shoe upper and lining; heating the stiffening piece to soften it and protecting the upper and lining from the heat; thereafter molding the stiffening piece to the form of the toe portion of the last while it is soft, by the operations of pulling over and lasting and allowing the stiffening piece to cool and permanently retain its molded form. 65

2. The method of making stiffened boxes of boot and shoe uppers, which consists of making a stiffening piece composed of fibrous material containing a stiffening composition or material adapted to be softened by heat of a degree which might be injurious to the upper and lining; fastening the stiffening piece to the upper; turning back the upper from the stiffening piece to protect it from the heat; heating the stiffening piece by a comparatively dry heat to render it soft and yielding; thereafter molding the stiffening piece to the form of the toe portion of the last while it is soft by the operation of pulling over the upper and allowing the stiffening piece to cool and permanently retain its molded form. 80

In testimony whereof, I have hereunto set my hand, in the presence of two subscribing 90 witnesses, this the 10th day of December, A. D. 1914.

RICHARD P. ELLIOTT.
